(57) **CLAIM**

The ornamental design for a charging device, as shown and described.

DESCRIPTION

FIG. 1 is a front perspective view of a charging device showing my new design;

FIG. 2 is a bottom view of the charging device thereof;

FIG. 3 is a top view of the charging device thereof;

FIG. 4 is a left view of the charging device thereof. The right view of the charging device thereof is a mirror image of the left side;

FIG. 5 is a rear view thereof;

FIG. 6 is a front view thereof;

FIG. 7 is another front perspective view of the charging device shown in use; and,

FIG. 8 is another front perspective view of the charging device shown in use.

The broken lines shown in the preceding drawings are for the purpose of illustrating the environment and form no part of the claimed design.

1 Claim, 5 Drawing Sheets
